(57) **CLAIM**

The ornamental design for a clock, as shown and described.

DESCRIPTION

FIG. 1 is a front elevational view of a clock showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a second perspective view thereof.

The broken lines illustrate portions of the clock that form no part of the claimed design.

1 Claim, 8 Drawing Sheets

FIG. 1

FIG. 3

FIG. 4

FIG. 5

FIG. 7

FIG. 8
